ALARM SENDING DEVICE

Tellef A. Terjesen, Orange, N. J., assignor to
 Signal Engineering & Manufacturing Company,
 New York, N. Y., a corporation of Massachusetts

Application January 31, 1938, Serial No. 187,780

7 Claims. (Cl. 200—42)

The present invention relates to a sending device for use in connection with the actuating stations of electrical alarm systems, to cause the operation of signals in response to the actuation of any station.

The sending device of the present invention is particularly adapted for a fire or burglar alarm system, in which the actuation of any station results in the continuous operation of the signals, without code significance. Alarm sending devices for such systems, as heretofore constructed, have usually provided a glass which, upon being broken, permits a spring-pressed plunger to close a circuit to cause continuous operation of the alarm signals of the system. While it is intended to permit the alarm signals to operate until the glass at the actuated station has been replaced by a person in authority, breakage of the glass at the actuated station exposes the plunger, so that it is possible for an unauthorized person to silence the signals by pressing in the plunger to break the alarm control circuit.

According to the present invention, there is provided an improved alarm sending device for use with a non-code continuous alarm signal system, which device is characterized by the fact that it can be actuated by a simple pull applied to a movable element. Furthermore, when once the movable element has been actuated to send an alarm, it is impossible to return the element to its original position to stop the alarm, without first opening the normally locked cover of the box containing the device. Therefore, the alarm will continue to sound until a person in authority has unlocked the box, whereupon reclosure of the cover will automatically silence the signals and restore the system to its original condition, in readiness for sending in another alarm. The above and other advantageous features of the invention will hereinafter more fully appear from the following description, with reference to the accompanying drawing, in which:

Fig. 1 is a view in front elevation, of an alarm sending device embodying the invention.

Fig. 2 is a vertical sectional view along the line 2—2 of Fig. 1.

Fig. 3 shows the device of Fig. 1, after it has been actuated to send an alarm.

Fig. 4 is a fragmentary sectional view, showing the position of some of the parts after the device has been actuated.

Fig. 5 shows the device with its cover opened, after being unlocked.

Fig. 6 is a diagrammatic view, showing the

connection of the device in an electrical alarm system, and also illustrating its association with a manually operated signal.

Fig. 7 shows a modification of the circuit of Fig. 6.

As best shown in Figs. 1 and 2, the device is illustrated in the form of a box, comprising a body 1, with a cover 2 hinged at 3, and a chamber 4, in which is mounted a block 5 of insulating material. A pair of contacts 6 are mounted on the insulating block 5, and in the normal, non-operating condition of the device, the contacts 6 are separated and no current flows therebetween. The space between the contacts 6 is adapted to be bridged by a conducting member 7 mounted on a plunger 8 extending through the block 5 in the direction of the cover 2. The plunger 8 is surrounded by a spring 9 located between the block 5, and a shoulder 2a, so that the spring 9 tends to urge the plunger 8 to the left to engage the bridging contact member 7 with stationary contacts 6.

With the cover 2 of the box closed, as shown in Fig. 2, the end of the plunger 8 bears against a plate 10 mounted on the inside of the cover 2, the thickness of the plate 10 being such that the plunger 8 is maintained in the position shown, with the spring 9 compressed and the bridging member 7 out of engagement with the contacts 6.

As best shown in Fig. 5, the plate 10 is mounted on pins 11 carried by the cover 2, with each pin 11 received in a slot 11a, so that the plate 10 can be moved longitudinally of the cover 2. A spring 12 urges the plate 10 upwardly, as viewed in Fig. 2, so as to maintain the lower ends of the slots 11a in engagement with the pins 11. In this position, the end of the plunger 8 is in engagement with the central portion of the plate 10, substantially opposite to an operating lug 13, which extends forwardly through a slot 14 in the cover 2. The lug 13 provides means accessible from the front of the box, whereby the plate 10 can be pulled downwardly against the pressure of the spring 12 to the position of Fig. 4, whereupon the compressed spring 9, surrounding the plunger 8, projects the end of the plunger 8 into a slot 15 provided in the plate 10. With the plate 10 in this position, the slot 15 registers with the upper end of the slot 14 in the cover 2, so that the plunger 8 can move far enough to permit the spring 9 to firmly engage the bridging member 7 with the contacts 6. As long as the end of the plunger 8 remains in the slots 14

and 15, it is impossible to move the lug 13 and its associated plate 10 upwardly.

In Fig. 6, there is shown diagrammatically, a simple circuit, in which bridging of the contacts 6 by the member 7 is adapted to cause energization of signals 16 from a suitable source S of electrical energy. As long as the contacts 6 remain open, the signals 16 are disconnected from the source S, and it is evident that upon actuation of a station by moving the lug 13 downwardly, the contacts 6 will be bridged and the signals 16 will be operated continuously. When once a station has been actuated by moving the lug 13, it is impossible to disconnect the signals 16 by moving the lug upwardly, since the end of the plunger in the lot 15 prevents movement of the plate 10.

When it is desired to silence the signals, a person in authority, provided with a suitable key, 20 operates a lock 17, consisting of a rotatable plate 18 on cover 2 cooperating with lugs 18a on body 1. Upon turning the plate 18 to disengage the lugs 18a, the unlocked cover 2 can then be swung forwardly toward the position of Fig. 5, whereupon the plate 10 is disengaged from the plunger 8 and the spring 12 is free to restore the plate 10 to its original position. Therefore, when the cover 2 is swung backwardly, preparatory to again securing it in position by the lock 17, the 30 plate 10 engages the projecting end of the plunger 8 to again move it to the position of Fig. 2. Therefore, the act of closing and locking the cover 2 automatically results in breaking the circuit between the contacts 6, and in silencing the 35 signals 16.

In order to indicate the condition of a station, the cover 2 provides suitable captions, such as "set" and "unset," cooperating with a shield 19 carried by the lug 13. When the station is in 40 readiness for operation, with the contacts 6 open, the shield 19 covers the caption "unset," while the caption "set" is exposed. When the lug 13 is moved downwardly to actuate the station, the shield 19 uncovers the caption "unset," 45 as shown in Fig. 3, indicating that the station is not in an operative condition, the caption "set" then being covered.

Although, as shown in Fig. 6, the actuation of a station to bridge the contacts 6 causes the signals 16 to be energized, the circuit can be readily 50 varied, as shown in Fig. 7, to provide for maintenance of a circuit between contacts 6a, by bridging member 7, in the normal non-operating condition of a station. This may be desirable for the purpose of supervising the contacts 6a 55 and member 7, and as long as the contacts 6a remain bridged, the winding 20 of a relay, in circuit with contacts 6a, remains energized. Therefore, when actuation of a station opens the contacts 6a, closure of the contacts 21 of the relay 60 serve to connect the signals 16 to the source S.

The actuation of a station by moving its lug 13, renders the station readily adaptable for use, in conjunction with a manually operated alarm signal. In some buildings, such as schools, it is 65 required that a manually operated alarm be provided, and in Fig. 6, a gong 22 is shown as being operable by a rod 23 extending between several floors of the building. In order to insure that operation of the rod 23 will also cause operation 70 of the electrically controlled signals 16, a chain 24 is connected to the lug 13 of a station at one floor. Therefore, downward movement of the rod 23 from any floor will not only sound the gong 22, but will also actuate a station to cause 75 operation of the electrically controlled signals 16.

From the foregoing, it is apparent that by the present invention, there is provided an improved alarm sending device for incorporation in the stations of a continuously operating, non-code electrical fire alarm system. Such a device, 5 when once actuated, insures the continuous operation of the alarm signals, until a person in authority can open the box of the actuated station with a key, whereupon the signals will be silenced upon closing the box cover. In this important respect, a station provided with a sending device of the present invention, is superior to the usual break-glass station.

I claim:

1. An electrical alarm sending device comprising a box containing relatively movable contacts, an operating member for said contacts, a cover for said box carrying a shiftable member adapted, when the cover is closed, to maintain said contact operating member in a given position and an element movable from the outside of said cover to shift said member and cause said contact operating member to alter the relation between said contacts, with said element being locked against return movement by said contact 25 operating member.

2. An electrical alarm sending device comprising a box containing relatively movable contacts, an operating member for said contacts, a cover for said box carrying a shiftable plate 30 adapted, when the cover is closed, to maintain said contact operating member in a given position and an element movable from the outside of said cover to shift said plate and cause said contact operating member to alter the relation 35 between said contacts, with said plate being locked against return movement by said contact operating member, as long as said box cover remains closed.

3. An electrical alarm sending device comprising a box containing a pair of relatively movable contacts, an actuating member for said contacts mounted on a spring-pressed plunger, a cover for said box carrying a movable element on the outside, and a plate on the inside connected directly to said element and engageable 40 with the end of said plunger when said cover is closed, movement of said plate by said element permitting said plunger to shift the actuating member with reference to said contacts.

4. An electrical alarm sending device comprising a box containing a pair of spaced contacts, a bridging member for said contacts mounted on a spring-pressed plunger, a cover for said box carrying a movable element on the outside and a plate connected to said element on the inside 55 of said cover and providing an opening, movement of said element permitting said plunger to pass through the opening in said plate to engage said bridging member with the contacts.

5. An electrical alarm sending device comprising a box containing a pair of spaced contacts, a bridging member for said contacts mounted on a spring-pressed plunger, a cover for said box carrying a movable element on the outside and a plate connected to said element on the inside 65 of said cover and providing an opening, movement of said element permitting said plunger to pass through the opening in said plate to engage said bridging member with the contacts, with said plunger maintaining said plate in its shifted 70 position while the cover remains closed.

6. An electrical alarm sending device comprising a box containing relatively movable contacts, a movable operating member for said contacts, a cover for said box carrying a movable element

5 on the outside and a plate on the inside of said cover connected directly to said element through said cover, said plate being normally adapted, when the cover is closed, to maintain said contact-operating member in a given position, with movement of said plate by said element causing said operating member to assume a different position with reference to said contacts, in which position said plate and cover prevent said contact-operating member from returning to its initial position, while said cover remains closed.

10 7. An electrical alarm sending device comprising a box containing relatively movable contacts,

an operating member for said contacts mounted on a spring-pressed plunger, a cover for said box carrying a movable element on the outside and a shiftable plate on the inside, connected directly to said element through an opening in said cover, with movement of said plate by said element permitting said plunger to shift the contact-operating member into a position in which the end of said plunger is received in said cover opening to prevent movement of said element 10 while said cover remains closed. 5
